UNITED STATES PATENT OFFICE.

JOSEPH R. PERRY, OF SOUTH NORWALK, CONNECTICUT.

DESIGN FOR A HEEL-PLATE.

SPECIFICATION forming part of Design No. 31,987, dated December 12, 1899.

Application filed November 13, 1899. Serial No. 736,880. Term of patent 14 years.

To all whom it may concern:

Be it known that I, JOSEPH R. PERRY, a citizen of the United States, residing at South Norwalk, in the county of Fairfield and State of Connecticut, have invented and produced a new and original Design for a Heel-Plate for Rubber Boots, &c., of which the following is a specification.

The invention relates to a new and original design for a heel-plate for rubber boots, gaiters, and the like; and it has for its object to provide a design of this character which will be both ornamental and useful.

The essential feature of the design resides in a heel-plate composed of an approximately segmental body portion provided with openings and having central and side lugs or projections and a curved bar provided with a stud.

In the drawings, Figure 1 is a perspective view of a heel-plate, showing my new and original design. Fig. 2 is a similar view, the heel-plate being inverted. Fig. 3 is a transverse sectional view.

Referring to the drawings, 1 designates a heel-plate provided with an approximately segmental body portion 2, having tapered or countersunk openings 3 and provided with a curved bar 4, offset from the outer face of the

body portion and extending from the approximately straight edge of the same at points 30 equidistant of the ends. The body portion 2 is provided at its ends with lugs 5, formed on its inner face and providing feet or bearings. The openings 3 are located between the ends of the body portion, which is provided with 35 annular bosses or enlargements 6, surrounding the openings and arranged at its inner face. The curved bar 4 is provided with a central stud 6^a, and the body portion has a central projection or lug 7 extending into the 40 space inclosed by the curved bar 4. The inner edge or face 8 of the body portion is composed of opposite straight portions and a central curved portion 9, from which the lug 7 projects. 45

What is claimed is—

The design for a heel-plate, as herein shown and described.

In testimony that I claim the foregoing as my own I have hereto affixed my signature in 50 the presence of two witnesses.

JOSEPH R. PERRY.
